United States Patent Office

Des. 224,147
Patented July 4, 1972

224,147

DIGITAL THERMOMETER

M. Louis Miller, Westfield, N.J., assignor to Victory
Engineering Corporation, Springfield, N.J.

Filed Mar. 9, 1970, Ser. No. 21,827

Term of patent 14 years

Int. Cl. D10—04

U.S. Cl. D52—7

FIG. 1

FIG. 2

FIG. 3

FIG. 4

FIG. 5

FIG. 1 is a view in front elevation showing my new design,

FIG. 2 is a view taken from one side thereof,

FIG. 3 is a top plan view thereof,

FIG. 4 is a rear view thereof; and

FIG. 5 is a somewhat isometric view thereof.

I claim:

The ornamental design for a digital thermometer, substantially as shown.
